JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed April 16, 1928. Serial No. 102,420.

This invention relates to typewriting machines of the type described in patent to Wernery and Smith, No. 1,132,055, dated March 16, 1915, wherein fan-fold work-webs are used in connection with ledger-sheets. The outer web is fed around the platen and a heading is typed thereon, after which it is fed upwardly until the plies thereof become freed or separated. A ledger-sheet is then inserted under or back of the front or top ply of the fan-fold web, and under a carbon-sheet. The pack so formed is turned backward or downward to bring the desired writing line to the typing position. In this backward movement of the pack sufficient friction is present between the plies and carbon-sheets to carry the ledger-sheet back therewith. The ledger-sheet is made wider than the web-forms and projects some distance beyond one side of the web-pack, and there receives typed matter not to appear on said web-pack. The free lower edge of the ledger-sheet springs away from the platen and strikes upon the forwardly-extending upturned edge of the front collating table, or passes outside thereof, thus stopping the downward and backward feed of the pack.

An object of the present invention is to eliminate the possibility of the lower edge of the free portion of the ledger-sheet catching on or contacting with the forward edge of the paper-guide. Means is provided for deflecting said free edge backwardly and behind the front edge of the paper-guide, in the backward movement of the pack to the typing position. An important feature of the invention resides in the provision of guide-devices, such as fingers or plates, preferably curved to substantially the arc of the platen, the free ends of the fingers lying slightly back of the edge of the usual paper-guide, and these fingers are by preference adjustably mounted on the usual web-severing knife. The knife is formed with a marginal flange extending from end to end, upon which the guide-fingers are frictionally and adjustably held by spring clip heads that are shaped to straddle and grip the flange.

Other features and advantages will hereinafter appear.

In the accompanying drawings,

Figure 1 is a fragmentary sectional elevation of a fan-fold typewriting machine, the section being taken on the line 1-1 of Figure 2, and showing a ledger-sheet inserted

around the platen, and illustrating how the guide-devices mounted on the knife deflect the free lower edge of said ledger-sheet back of the forward edge of the paper-guide, when said sheet is moved down toward the typing position by the web-pack when the platen is turned back.

Figure 2 is a front elevation of some of the parts shown in Figure 1, and shows the manner of interleaving the ledger-sheet with the fan-fold pack and also shows the guide-devices and the manner of positioning them on the supporting knife in front of and over the free extended portion of the ledger-sheet.

Figure 3 is a detail perspective view showing a portion of the knife and the guide-devices mounted thereon.

The platen 5 is mounted in the usual carriage 6, back of which is the usual work-frame 7. Rolls 8 and 9 co-operate with the platen 7 to feed work-sheets, or packs around the platen.

The usual rear paper-table 10, with its forward curved guide-portion 11, terminates in an upwardly and forwardly directed edge 12.

In carrying out the present invention, the knife 13 is formed preferably at its front edge with a flange, rib or bead 14, on which the guide-devices 15 (two being here shown) are adjustably carried and which are preferably formed of sheet spring metal. Each guide-device comprises a head 16 and an integral plate or finger 17 longitudinally curved on an arc substantially corresponding to the arc of the paper-guide and platen. The free ends 18 of the guide-fingers lie just below and inside the edge 12 of the paper-guide as shown in Figure 1.

The heads 16 of the guide-devices 15 are formed into clips to frictionally engage the flange 14 of the knife 13. These clips have spring side portions 18 and a connecting top portion 19 which rests on the top of the flange 14 when the guide-devices are mounted in operative position. As shown, the guide-fingers 17 are formed integral with the forward spring sides of the clips and constitute extensions thereof.

Referring to Figure 2 of the drawings, there is shown a ledger-sheet 20 and a fan-fold work-web 21 mounted on the platen 5.

When ledger-sheets are employed in connection with fan-fold work-webs, two carbon-sheets 22 are interposed between the first and second plies or sheets of the web, and, be-

tween these carbon-sheets 22, the ledger-sheet 20 is inserted as shown, but being purposely made wider than the work-web it extends or projects some distance beyond one side of the web, as shown at 23, and the lower edge of this free unconfined extended portion springs out or moves away from the platen 5, and, when the web-pack carrying the ledger-sheet is backed into the machine toward the typing position, the lower edge of the ledger-sheet will strike the forward edge 12 of the paper-guide and stop the back-feed movement.

The improved guide-devices above described prevent this contact of the parts by deflecting the loose free edge of the ledger-sheet inward and back of the forward edge of the paper-guide, thus allowing free passage of the interleaved forms and ledger-sheet back and to the rear of the platen to the typing position.

It will be understood that changes in the construction of the features of this invention may be resorted to, for example, the flange formed on the knife may be on the underside thereof or it may be formed along the longitudinal center of the top face and may take various cross-sectional contours, for instance, it may be rounded or dovetailed and curved plates may be substituted for the guide-fingers, which may be attached to the knife in any approved manner.

Variations may be resorted to within the scope of the invention, and portions of the improvements may be used without others.

Having thus described my invention, I claim:

1. In a fan-fold typewriting machine, the combination with a platen, a front paper-table extending above the platen at the delivery side thereof, a rear paper-table having a paper-guide extending around the under portion of the platen and ending at the front below the printing line thereof, and feed-rolls for feeding a fan-fold web inserted at the rear side of the platen in a forward direction, and for feeding the same rearwardly together with a front-inserted independent work-sheet wider than the fan-fold web positioned between the plies of a set of forms of the fan-fold web, while the forms are fed to an accessible position above the front of the platen with a portion of the wide work-sheet extending beyond the side of the fan-fold web, of means for guiding said extending portion of the work-sheet during the rearward feeding of the fan-fold web by said feed-rolls together with said work-sheet, consisting of one or more fingers extending from a position adjacent the lower edge of the front paper-table downwardly between the paper-guide and the platen, so that the edge of the extending portion of the work-sheet will not contact with the edge of the paper-guide during the downward movement of the sheet into said paper-guide.

2. In a fan-fold typewriting machine, the combination with a platen, a front paper-table extending above the platen at the delivery side thereof, a rear paper-table having a paper-guide extending around the under portion of the platen and ending at the front below the printing line thereof, and feed-rolls for feeding a fan-fold web inserted at the rear side of the platen in a forward direction, and for feeding the same rearwardly together with a front-inserted independent work-sheet wider than the fan-fold web positioned between the plies of a set of forms of the fan-fold web, while the forms are fed to an accessible position above the front of the platen, with a portion of the wide work-sheet extending beyond the side of the fan-fold web, of means for guiding said extending portion of the work-sheet during the rearward feeding of the fan-fold web by said feed-rolls together with said work-sheet, consisting of one or more fingers extending from a position adjacent the lower edge of the front paper-table downwardly between the paper-guide and the platen, so that the edge of the extending portion of the work-sheet will not contact with the edge of the paper-guide during the downward movement of the sheet into said paper-guide, and means for adjusting said fingers longitudinally of the platen to accommodate fan-fold webs and work-sheets of different widths.

3. In a fan-fold typewriting machine, the combination with a platen, a web-severing knife extending across the platen and above the printing line, a paper-guide extending around the under portion of the platen and ending at the front below the printing line thereof, and feed-rolls for feeding a fan-fold web inserted at the rear side of the platen in a forward direction, and for feeding the same rearwardly together with a front-inserted independent work-sheet wider than the fan-fold web positioned between the plies of a set of forms of the fan-fold web, while the forms are in a position beyond the severing knife, with a portion of the wide work-sheet extending beyond a side of the fan-fold web, of means for guiding said extending portion of the work-sheet during the rearward feeding of the fan-fold web by said feed-rolls together with said work-sheet consisting of one or more fingers extending from said web-severing knife into the front end of said paper-guide, so that the edge of the extending portion of the work-sheet will not contact with the edge of the paper-guide during the downward movement of the sheet into said paper-guide.

4. In a typewriting machine having a platen, a paper-guide, and means for feeding a web-pack and a ledger-sheet wider than the pack-sheets and extending beyond one side thereof and free therefrom, a knife having a flange along its forward edge, and

- guide-devices frictionally carried on the flange and supported above the forward edge of the paper-guide, forward of and over the free extended portion of the ledger-sheet, 5 each of said devices including a head having spring sides and a curved finger formed integral with the head and extending downwardly from the outer spring side of said head.
- 10 5. In a typewriting machine having a platen, a paper-guide, and means for feeding a web-pack and a ledger-sheet wider than the pack-sheets and extending beyond one side thereof and free therefrom, a knife ar- 15 ranged over the platen and having an up-
- wardly-directed longitudinal flange at the forward edge thereof, and adjustable guide-devices supported by the flange and positioned in front of the free extended portion of the ledger-sheet and above the paper-guide, said devices each including an elongated channelled head having spring sides to engage the sides of the flange, a connecting top portion bearing on the top of the flange, and an integral finger projecting centrally from the forward spring side, said finger being curved, its lower end terminating slightly below and back of the forward edge of the paper-guide. 20 25

JESSE A. B. SMITH.
